CLAIM

We claim the ornamental design for a cup, as shown and described.

DESCRIPTION

FIG. 1 is an upper perspective view of a cup.

FIG. 2 is a front view thereof.

FIG. 3 is a rear view of FIG. 2.

FIG. 4 is a left side view thereof.

FIG. 5 is a right side view FIG. 4.

FIG. 6 is top view thereof; and,

FIG. 7 is a bottom view of FIG. 6.

The broken lines in the drawing depict portions of the cup that form no part of the claimed design.
